UNITED STATES PATENT OFFICE.

ELMER BRADNER WHITE, OF MARYLEBONE, LONDON, ENGLAND.

SAFETY-RAZOR-BLADE HOLDER FOR STROPPING PURPOSES.

1,084,682.

Specification of Letters Patent.

Patented Jan. 20, 1914.

Application filed May 13, 1913. Serial No. 767,253.

To all whom it may concern:

Be it known that I, ELMER BRADNER WHITE, a citizen of the United States of America, residing at 30^a Wimpole street, 5 Marylebone, in the county of London, England, have invented certain new and useful Improvements Relating to Safety-Razor-Blade Holders for Stropping Purposes, of which the following is a specification.

10 This invention relates to safety razor blade holders for stropping purposes and has particular reference to blade holders of the kind in which the blade is gripped between two hinged members.

15 The chief object of the present invention is to provide a blade holder that is simple in construction, easy to manipulate, and capable of holding the blade firmly at the correct stropping angle.

20 According to this invention the two members of the blade holder possess freedom of relative movement in two different directions which are such that one movement enables the blade to be embraced by the said

25 members while the other movement results in the members becoming firmly clamped together. In one convenient constructional form of the holder one member is secured to or integral with a handle of any appropriate kind, and the other member is hinged in such a way that it is not only capable of being moved angularly about its hinge but also of being moved bodily with respect to its hinge in an axial direction. A catch or

30 fastening of any appropriate kind is adapted to hold the two members together in their blade retaining position with the blade between them. A simple form of fastening is constituted by a dovetailed lug on one member adapted to engage in a corresponding slot or groove in the other member when the two members are axially adjusted relatively to one another.

35 In order that the said invention may be clearly understood and readily carried into effect, the same will now be described more fully with reference to the accompanying drawings, in which:—

40 Figure 1 is a side elevation of one embodiment of the invention, the two members of the blade holder being shown in their open position; Fig. 2 shows the members merely folded up; and Fig. 3 shows them in their folded up and axially adjusted position. 45 Fig. 4 is a section on the line 4—4 of Fig. 3.

A is the handle of the blade holder, B the

stationary member, and C the movable member. The members B and C are connected by the hinge pin D on which the member C is capable of sliding axially to an extent limited by the shoulders b^o on the member B. Although the invention is of course applicable to the stropping of plain blades or blades having positioning notches, grooves or slots, the particular construction of blade holder illustrated is adapted for holding punched blades of the kind that have holes for the reception of the positioning pins of the holder in which the blade is held for shaving. Centering pins b on the member B are adapted to engage the holes in the blade, and recesses c in the member C serve to receive the projecting ends of the centering pins when the two members are folded together.

50 In using the holder, the blade to be stropped is placed in position upon the stationary member B, and the movable member C is then folded over about its hinge from the position shown in Fig. 1 to that shown 55 in Fig. 2. The said movable member is then moved axially on the hinge pin D from the position shown in Fig. 2 to that shown in Fig. 3. This axial movement of the member C causes dovetailed projections c' c^o on the member C to fit into dovetailed slots b' b^o on the inner face of the member B, thereby locking or clamping the two members firmly together. The angle contained 60 by the outer surfaces of the two members 65 of the holder when clamped together should be the angle most suitable for stropping, namely about fifteen degrees (15°) so that the edge of the blade is always presented to the stropping surface at the correct angle. 70

75 It will be observed that the blade holder proper is connected to its handle in such a way that the blade can be stropped upon an ordinary strop in the manner adopted with ordinary razors.

80 What I claim and desire to secure by Letters Patent of the United States is:—

85 1. A safety razor blade holder for stropping purposes, comprising a handle, two blade retaining members angularly and axially movable relatively to one another, means connecting the said members with freedom of relative angular movement, means limiting their relative axial movement, and means for locking the members together.

90 2. A safety razor blade holder for stropp-

ping purposes, comprising a handle, two blade retaining members, one member being rigid with the handle and the second member angularly and axially movable relatively to the first, means connecting the said members with freedom of relative angular movement, means limiting their relative axial movement, and means whereby axial movement of the second member relatively to the first effects a locking of the two members together.

3. A safety razor blade holder for stropping purposes, comprising a handle, two blade retaining members, one member being rigid with the handle and the second member angularly and axially movable relatively to the first, means connecting the said members with freedom of relative angular movement, means limiting their relative axial movement, and means on said members for interengagement when the axial adjustment is effected.

4. A safety razor blade holder for stropping purposes, comprising a handle, two blade retaining members, one member being rigid with the handle and the second member angularly and axially movable relatively to the first, means connecting the said members with freedom of relative angular movement, means limiting their relative axial movement, and a projection on one member, the other member having a corresponding slot, said projection and slot being situated and shaped to interlock when the axial adjustment of the movable member is effected.

5. A safety razor blade holder for stropping purposes, comprising a handle, two blade retaining members, one member being rigid with the handle and the second member angularly and axially movable relatively to the first, means connecting the said members with freedom of relative angular movement, means limiting their relative axial movement, and a dovetailed projection on one member, the other member having a corresponding slot, said projection and slot being situated and shaped to interlock when the axial adjustment of the movable member is effected.

50 6. A safety razor blade holder for strop-

ping purposes, comprising a handle, two blade retaining members, one member being rigid with the handle and the second member angularly and axially movable relatively to the first, means connecting the said members with freedom of relative angular movement, means limiting their relative axial movement, and dovetailed projections on one member, the other member having corresponding slots, said projections and slots being situated and shaped to interlock when the axial adjustment of the movable member is effected.

7. A safety razor blade holder for stropping purposes, comprising a handle, two blade retaining members, one member being rigid with the handle and the second member angularly and axially movable relatively to the first, means connecting the said members with freedom of relative angular movement, means limiting their relative axial movement, and centering pins projecting from the internal face of one of the members, the other member having corresponding recesses on the internal face, and means for locking the members together.

8. A safety razor blade holder for stropping purposes, comprising a handle, two blade retaining members, one member being rigid with the handle and the second member angularly and axially movable relatively to the first, means connecting the said members with freedom of relative angular movement, means limiting their relative axial movement, centering pins projecting from the internal face of one of the members, the other member having corresponding recesses on the internal face, a projection on one member and a corresponding slot in the other member, said projection and slot being situated and shaped to interlock when the axial adjustment of the movable member is effected.

In testimony whereof I affix my signature in presence of two witnesses.

ELMER BRADNER WHITE.
